Daniel Pittibone. Patented May 12, 1812.

To all to whom these presents shall come, greeting:

I certify, That the annexed is a true copy of a patent given to Daniel Pittibone for an improvement in warming rooms, or apartments, by means of rarefied air, applicable to ovens, drying, hot or green houses, rooms &c.

In Faith Whereof, I James Monroe Secretary for the
Dept. of State of the United States of America
have signed these presents, and caused the seal of my
Office to be affixed hereto, at the City of Washington the
Twenty eighth day of April A. D. 1813 and in the
thirty seventh year of the Independence of the United States.

James Monroe

(Patented May 12, 1812)

The Schedule referred to in these letters patent and making
part of the same containing a description in the words of the
said Daniel Pittibone himself of his improvement for warm-
ing rooms or apartments by means of rarefied air, applicable
to ovens, drying, hot or green houses, rooms &c.

The improvement of the rarefying air stove, or the invention
of the same consists in the construction of a stove or fire-pipe
with a large rarefying air -reful or chamber, connected with
the same, or things as hereinafter described. — These air-
refuls or chambers, are so constructed, as to contain any kind
of stone, or steam pipe, or an air-reful is placed in any stove
so that the air is heated in contact with the outside of the stone
or steam pipe, or within the stove in the air-reful.

The invention for this consists in applying to any iron
reful, any pot, kettle, boiler, tube, pipe, cylinder, or other
apparatus for heating air the same as may be used for heat-
ing of water &c. These pots, kettles, or boilers may be set in
an iron case with a hoop of three or four inches in width,
soldered or riveted to the sides near the bottom, or in an

double wall of brick, similar to or still or better receiving
into them at or near the bottom a large supply of pure, fresh
external atmospheric air from the street, cellars, or yards
by means of one or more tubes or pipes to conduct or con-
vey the external air into the pot storage boiler & from the
pot store or boiler into the rooms or rooms to be warmed,
or into a kitchen or scullery, which may be lined with
pulverized charcoal to prevent the escape of heat thru
its sides, charcoal being a bad conductor of heat, ...
the heat may be conveyed in tin, paste-board sheet iron
or clay pipes, to any room or apartment. And more opportunity
to preserve or economize the heat, the pipes may also be coated
with charcoal, or made double, so as to have a dead column
of air between, or be covered with several thicknesses of brick
clay. All these pipes or tubes must have stops made, so as
to regulate the passage of heat at pleasure. Hence this kind
of stove may be so constructed as to produce heat sufficient
to warm fifty rooms in a dwelling house or Hospital 800.
and after the heat is conveyed to the ground deposit or exterior,
it may be taken off by pipes, in a similar manner
as a city is supplied with water from a reservoir, and
conducted to any room or apartment, as required. It is
to be observed, that rooms or apartments not to be warmed
should be ventilated at or near the floor. Small open fire
places or tubes, leading from the floor to the top of
the building, will answer very well. These ventilating
tubes or fire-places should be so fitted with registers or valves
as to regulate the ventilation, as circumstances may require.

When it is found that the external air is warm and
the apartment is crowded with people, it is proper that
ventilation should take place at the top, at or near
the ceiling. Whenever an apartment is fitted with con-

terminated air, particularly in the summer by the perspiration of breath or exhaled air, or from the burning of candles, lamps, &c. for any other cause, it is of much consequence that double, thin, flat board or other tubes filled between with charcoal should be placed just above the lights, and connected to the external atmosphere by blowing air or smoke of burning fat into lamps in or near the end of the tubes. The air in the tubes becomes rarefied, and by the current of air up the tubes the ventilation is made to be more complete.

There may be many dispositions of this principle of the principle and the modifications of the apparatus summarized.

The common chimney or open fire-place, also the common open stove (called the Franklin fire-place) is very much improved, by placing an air-vessel upon it, and sometimes a hollow cylinder in place of a back log in it, or just above the fire. The flame knock by passing round the air-vessel in a reverberatory manner, communicates their heat to the air in the air-vessel which air is introduced into the air-vessel from the exterior atmosphere, as before described and let into the room, or to an adjoining room from the sides or top of the stove. The air-vessel in the common chimney fire-place, I place just above the fire or the kindled fire or the mantel (if it is low) and then admit the warm air into the room just above the mantel-tree. Considering the upright heat directly over the fire, to be much the greatest, except in contact with or in the midst of the kindled oals. Therefore I have constructed, upon more cheap and improved plan, a metallic box (being an air-vessel) composed of thin sheet or cast iron plates. This box must be adapted to the shape of the chimney or other fire-place and so closely fitted to the back and jamb as to prevent the escape of heat to smoke except out of the room where air or sufficient must be left as a draft for the

smoke. It may be necessary to have several boxes, one above the other, connected with short tubes or pipes. The external air entering the lower box will issuing from the uppermost by pipes into the room under or above the mantle, through a plate of iron or a marble block. If only one box is applied to the chimney, it is best to have the upper part double, leaving a dead column of air (using a iron condenser) to prevent the escape of heat. - If these boxes are made of iron plates, they should be painted black, to prevent the escape of heat by reflection. In fitting these boxes, dampers or registers may be used, to preserve too great a draft or ventilation and they might be of further use if the chimney should happen to be open to prevent a frost, or all the current from descending - By which means the fire would be immediately extinguished.

In some instances . . . I have caused air-pipes to pass directly through the fire perpendicular, or horizontally, among the kindled coals - just above them. - I have made grates with hollow bars, for the purpose of heating either air or water.

It hollow cylinder, of six or eight inches diameter, made of the stoutest sheet-iron, or a made of cast iron and in place of a back-log would answer better; the external air entering at one end, or at any other part of the cylinder would pass into the air-vessel above the fire, or immediately into the room, or rooms or to an adjoining room or room. All times, I introduce water into these grates or cylinders the steam of which I apply by means of pipes to many useful purposes. Such as heating air in tubs or casks in contact with the steam pipes or preserving warm baths in chambers &c. In all cases where there are open fire places the inlet of warm air should be in the proportion to that which is drawn out, to prevent the cold

air rushing in at the doors, windows, or vines &c.

For this improvement on the common chimney and open fire-place ^{Fig 3}: After adding the old invention of a hollow hearth, back and jambs of iron public hot in Paris in the year 1709, or a proper open stone, or fire-place of cast iron purposely furnished or fitted - You then or constraint the flue with iron plates just within the Mantle-piece, enclosing an iron or clay pipe, which pipe must pass up the chimney flue to the top so nearly as to conduct off the smoke.

The chimney must be stopped up at or near the top by arching with bricks so to have the aperture for the down smoke-pipe free.

This may be swept from the top or from an opening in the chimney in the garret above a brush scupper and might be attached to a cord, and this opening in the chimney may be closed with an iron door - The external air being admitted through a hole of six, eight or more inches in diameter under the hearth the fire in contact with the outside of the heated iron pipe - And may be transmitted through some holes in the chimney, in the different apartments and regulated at pleasure with valves or registers. It is to be observed, that an apartment may soon be cooled or ventilated by making a hole in the chimney flue near the ceiling and by unstoping the chimney flue where it has been closed and stopping the external air hole at the bottom under the hearth. By this means, the contaminated or foul air of a room will be drawn out of it, up the flue of the chimney - Therefore a fire in a lower most room with charcoal or ventiles the upper or middle rooms in the summer, if fire according to the above improvement.

I would advise to build chimneys with only one flue either oval round or square - commencing at the first

1730 X

floor, without any divisions, sufficiently large to admit as many iron or clay pipes as there may be fire-places, grates or stoves in the different stories as required in the common mode of having chimneys. In those cases where the fire-place is erected without hollow backs, jambs, or hearths, the flue of the chimney must be closed just above the mantel-piece, so as to include an iron pipe or funnel as before described, to convey the smoke (the chimney being sealed above, as before mentioned). And to this pipe one or more air-pipes may be constructed, which serve to retain an additional quantity of heat from the fuel. In this constructed fire-place, the external air must be admitted into the chimney flue, just above the enclosure near the mantel-piece to which may be adapted a dampener or register; and the chimney flue is furnished with issues holes to allow the heated air to pass out into the different apartments.

It is of consequence to place pieces of iron pipe or funnel, in the chimney flue, especially opposite the lower or middle rooms, the inner end, which spread wide, to catch the current of the heated air in its recession within the flue.

I have constructed an apparatus, so as to convey the external air through the medium of tubes, or portable hollow backs or hearths terminating in several holes (supplied with dampers) so that the air may enter among the coals, placed in a fire-place grate or stove, and close these in a similar manner to a smith's forge. Hence this is called the external blower.

Further. One or a number of common iron hottes may be placed, inverted, on a furnace erected for that purpose, over which an arch may be made with bricks, or a furnace made sheet iron, triplite double, or a wooden frame, properly battened and plastered, (which is far better than bricks, if a suitable fence from the heated iron) this arch or furnace is suspended above, so to have a sufficient space between the convex part of the hottie and the concave part of the arch or furnace, so as to admit a sufficient portion of external air, by

means of a large tubes or openings, near the bottom, the kettle may be placed on a line, or in a cluster of three or four together.

The fire is then applied, and the air is heated on the external sides of these kettles and when heated it passes up in one large tube, or through several pipes introduced into the concave part of the upper part of the funnel or allow the heated external air to escape into the apartment to be warmed, while the smoke is conducted off in a reverberatory manner, under the kettles, and then up through an iron pipe in the center or through pipes or flues of brick made as in ordinary.

I apply to use all kinds of stoves, or things, that give heat from fuel in combustion free from smoke, whether it be globular, semi-globular, square or cylindrical and heat the external air in an air reflector inside of the stove, or in contact with the hot sides. I have found it of consequence to place the kettle or stove outside of a building, or under shade - And expose the stove to the open air, as if it stood in the open field.

When I suspend a funnel over the kettles or stove resembling a common tin funnel, such as is used for lighting of kettles except that it is made double or triple, allowing the air to pass up between into the main pipe that enters the upper part of the apartment to be warmed, which main pipe is to be opened or constricted according as the heat escapes from the stove or kettle.

I can additional evidence of the utility of this principle, and of my improvement - nearly all the heat generated from the combustion of the fuel used, may be saved and transmitted at pleasure by Fifty, one or two, cast iron tubes or boxes either cylindrical, and square, or flat, placed one above the other (somewhat similar to the boxes of a common still in its effect) in the brick or iron wall - in a grating resembling net-work, sufficient to hold plaster mortar or cement instead of Bricks by which I form a kind of oven or reservoir of heat, by enclosing the tubes or boxes in it.

In these flat-mould boxes (as I beg leave to term them) I place a division plate, standing edge wise, which causes the smoke to pass twice across the oven in each box, before it rises into the next.

These tubes or boxes are open at one or both ends at pleasure when the seat is to be taken out. The apertures for the removal of the seat appear through the bricks with the flue underneath these tubes or boxes I frequently apply a stove very much like the common one, known by the name of the iron or iron plate stove or iron stove. In this common stove, two plates only are exposed to the upright flues, the one under the oven & the other at the top. It often happens that the upper plate called the oven-plate, is too hot, which generally burns the bread. To prevent this, bricks are often used in the oven. Another circumstance, very disagreeable, is, that the fumes of the oven are admitted into the room and occasions the air in the room to be very unpleasant and unfit for respiration.

To remedy this inconvenience, I have made the following improvement. The oven-plate is a cast iron grating or grid work sufficient to hold clay, mortar, cement, & plaster which holds the heat similar to a common brick oven; the heat being gentle and regular, prevents the articles from burning that are put upon it.

I sometimes make the oven-plate of two thin plates of wrought or sheet iron, with an inter medium of clay or mortar, instead of the outside of the stove ^{the outside of the stove is made of cast-iron plates, or common, or iron} work and plaster. I cause the flue to pass through the oven in a sheet or cast iron tube or flue, which is in size about four inches by eight, or so as to be two or three inches narrower than the body of the stove.

The advantage of this tube passing through the oven is that more heat is retained, so as to bake the upper part of the wall as the bottom.

3. Ventilation is the next in order of importance. It not only adds to the flavor of the articles baked or cooked, but tends to expedite the process. In order to perform this operation, a cast iron wrought iron pipe or tube of the size of a gun barrel should be placed in the hottest part of the stove under the oven plate, and one end connected with the air of the room, or the external air, which is preferable. The other end is to enter the oven through the oven plate at the back end of the plate or oven. This is to rise nearly to the top. There then another pipe leading downward from the outer side of the smooth tube or flue, within the oven near the oven plate. In this oven, as the hot air from without enters the top of the oven, it forces the former downward to enter the pipe that leads into the smooth flue. Dampers or registers are placed in the pipe to regulate the current of air going in or out of the oven, to ventilate it more or less.

4thly. When this stove is enlarged with a number of flues or smooth boxes, one above another, it is intended for baking of meat, bread, pastry, drying fruit &c. Openings are made in the sides, to admit iron drawers, furnished with wire net work bottoms; sheet iron however, with preparations, may answer the same purpose. These drawers are intended to slide in between the boxes or flues to rest upon them, which in fact appears like a case of drawers. When this stove, oven, or apparatus, is used for warming rooms, a large supply of external air is admitted, which comes in contact with the heated stove, boxes, and flues.

When it is used for cooking, baking, drying fruit &c. no current of air is employed, as before described.

The fire in the stove should be blown with external air, as should be the case with all stoves at times. By external air, I mean air from without the house. A strong current of air, if it enters directly under the burning fuel, will

cause the smoke to go in any direction, either direct to the top of the stove or to descend in all the corrisiding passages, like the steam in the warm pipe of a common still. It will then ascend in a pipe or the chimney flue.

6. I very much improve the common baking stove already in use by altering it to an air stove; or by cutting a hole in the plate above the oven, to discharge the fumes. to which hole a register is fitted, to let off more or less as circumstances may require.

7. Stove or apparatus of any proper size of the semi-jacketed or any other convenient form, with a proper fire place under it, enclosed in bricks forming a double wall, in a similar manner as employed for warming rooms, may be used for ovens, or drying houses &c. &c. These ovens, or drying rooms may be made of any size and materials, according to the different degrees of heat required. ~~especially~~ for drying of clean paper &c. for rations &c. A room made of wood with pretty lathes and plastered inside, made a wall of bricks at two or three inches distance outside, so it answers. It also will be found to answer exceedingly well for a clothes-tum washing room &c. as it will perform the operation equal and much sooner than the rays of the sun. And can be appropriated to great advantage in drying barley, malt, corn, meal, flour or fruit with less danger and expense than the common mode of hating drying.

8. When the oven is intended for drying japanned or varnished ware, or for any kind of cooking, it must be made arched at the top with bricks &c. either sheet iron or tin plates double at the top, sides, filled between with hair or finely pulverized. It should be supplied with shelves of tiles, iron or wire net work.

This may be made of various forms and shapes. And when the oven is made in semi-circular form one or more iron wheels

(With an iron bell-weather roof, another suitable substance for the articles to lay on) may be placed in it horizontally, or an upright shaft which wheels or wheels pass through the stone or oven, on one part of which unbaked bread or other articles such as seeds of all kinds for the purpose of drying or oven may be placed, and by turning the wheel round the articles are carried through to the heated air in the oven or stove and come out baked on the other side. These wheels may be moved by weights as a clock or by the hand.

I do at pleasure introduce into the oven stone or drying room hot air steam, or cold air as circumstances may require and regulate the same by stop-cocks, registers, or dampers - those different air being all fresh, completely ventilates the air in the drying room so and carries off all kinds of vapours with the smoke flue, or by pipes into the open air. X

Further to Brasses, &c. &c. For warming rooms, the following method is proposed. A close stone or common open fire-place, made of flat-wire bricks, stone, or other suitable materials, above which is constructed one two or more plain square flues, of iron or of bricks, or of pottery, rising to any proportionable height, say four to five feet - The one flue to receive into it the external air and the other for the smoke, all the flues are so nearly closed at the top. The smoke at the top enters an iron pipe on the chimney flue in which pipe a register or damper is placed and the smoke is conveyed off into the common stove, or may be made to descend in another flue (which must be added) and rise again to the top... where it then escapes. In these smoke flues are placed short pieces of square or round tubes or pipes made of sheet or cast iron, tin or clay. If of clay they are most conveniently made round by the potter's wheel, & burnt in

another ware. These pipes or tubes pass across the smooth flue, into the air flue, one above the other, at short distances, and although they are not placed directly over each other, yet they are situated, first on one side & then the other, leaving about two thirds of the flue. Each pipe on the flue is a round and closed in a zig-zag manner. This heat ^{into the apartment by a current of warm air} is admitted from each tube or pipe. The tubes or pipes are smallest at the end next the air-flue and are taken out where the soot is to be removed from the flue. This stove is best not to be immediately connected with the brick walls of a house, as the walls may have a tendency to absorb too much of the heat. Further more I can prove the common chimney fire-place by turning the flue & smoke from its usual course into the room within an iron flue, which flue rises nearly to the ceiling, then enters into the chimney flue. Which iron flue is at the lower end next to the fire place about 18 inches wide, and at the upper end next to the ceiling about six inches, & in depth only three or four inches. However the shape may be varied as fancy directs. — These stoves may be made to represent a Pyramidal, or Pillar. Or may be formed to any other shape for the purpose of ornament & utility, — my stove or rather a reservoir of heat may be made to represent a column in the center of which a pipe or flue is placed. The smooth is made to pass round the flue from the bottom to the top in a spiral or serpentine direction, which is done by means of bricks so formed as to convey the smooth air in this way. The stove or column is furnished with tubes or boxes as before described. When the smooth has risen to the top of the column, it is carried off in the common stove. Or may be made to turn down thru the center of the air flue. — In this stove or reservoir no appearance of pipes or flues for the smooth is seen

as in other stoves; on the contrary it may be so decorated as to render it an ornament to a Room.

I have constructed a cylindrical stove standing perpendicularly or horizontally, when made perpendicular it resembles a common Copper pot, excepting that it has two spouts & two handles, these spouts being opposite to each other, serve as reservoirs or places to put in the fuel, without disturbing the fire as in the common stove.

When lying horizontally the fuel is put in at one end or at the side, similar to a common air furnace (into the inner or outer cylinder). It being composed of two cylinders and the air being heated in the inner or between the two cylinders, and suffered to escape at the top of the outer cylinder.

The application of the following plan is manifestly advantageous in warming and ventilating merchant ships and vessels of war. Fig. A boiler or an air vessel may be fixed in the furnace or fire-place in the barge, to the bottom of the boiler a tube is introduced, which issues from it down the inside of the ship or vessel nearly to the keel, where it forms a curve & turns upwards above the deck. At this place it admits the external air, which passes through the tube into the boiler, & after it is heated it passes out of another tube inserted into the uppermost of the air vessel, and the heated air may then be conducted into any part of the ship or vessel. These tubes must be made double, and the intermediate space between the tubes should be filled with pulverized charcoal to prevent the escape of heat where it is not wanted. Also if the receiving tube penetrates into the hold of the ship, and conveys it into the boiler, and after being heated thence into another tube fixed into the supercior part of the boiler, which conveys it in to the

atmosphere above the deck, where it mixes with the general air. This improvement can be very easily & easily applied to ventilate stoves, beds, school rooms, and any apparatus or place infregnated with foul air. To effect this in out warming the room, the boiler or stove should be placed above it. But to warm as well as to ventilate it should be placed below. In some places supply steam for warming & ventilating apartments, & particularly where the utmost safety is required, such as gunpowder factories &c. But instead of steam-pipes being placed in that apartment the heat is emitted into them by current of cold air, which air has been previously heated in contact with steam-pipes, tubes or various other apparatus. Supply boiler or things of various form to make steam supplied with safety valves, grates with bars, or one or more hollow cylinders, to prop water from the fire, not only to prevent the grates or apparatus from being destroyed by the fire but also to create steam, or hot water for the purposes of warming &c.

I claim no particular improvement in heating by steam passing in a worm-pipe. The pipe is that to say that the transporting of heat to apparatus to be warmed by a current of fresh air heated by boiler, or steam what I claim. A boiler & worm-pipe is nothing similar to a common still, but never that is to say instead of applying steam into the upper end of the worm-pipe, the worm-pipe being there so that the steam enters into it at the bottom. The top of the condensing tube is upward, which causes the worm-pipe so the steam rises from the boiler to top of the worm-pipe being closed so that it cannot escape. The steam is condens'd with a current of cold air entering in contact with the steam-pipe. Which air is

heated rises through pipes to the apartments to be warmed, through the bottom of the containing tube.

In all cases as the steam is condensed to water it returns back to the boiler, so that there is little or no waste of water from the boiler. Instead of a warm pipe, a pipe passing in a zigzag manner within a hot water box, or one globe, box pipe, or cylinder placed within another either the steam entering the external globe or cylinder No. 8 from rising air in the exterior globe or cylinder or the steam entering the internal, not heating the air between the two. In this I apply tiles, cast-irons, or boxes of any suitable size, into which tiles, cast-irons or boxes I force steam or hot water, and through these tiles, cast-irons, or boxes, I force pipes or tubes of tin, or made of other proper substance either perpendicular or horizontally, at one end of these pipes or tubes the cold external air enters and by passing through the pipes or tubes within the hot water or steam, it becomes heated and (as before mentioned) rises by means of pipes to the apartment to be warmed.

In this mode twenty or more apartments in one house can be warmed one or all at the same time by opening & shutting cocks or valves &c.

Portable drying rooms or ovens, constructed on this plan might be used for drying wet gun powder and wet cartridges in the army, and prevent many disasters that might result therefrom.

Witness

Daniel Pittibone
